Primary Examiner — Kendra Leslie Hamilton*Assistant Examiner* — Amanda Christensen(74) *Attorney, Agent, or Firm* — PATTERSON + SHERIDAN, LLP; Chad M. Dougherty(57) **CLAIM**

The ornamental design for a chamber inlet, as shown and described.

DESCRIPTION

FIG. 1 is a top plan view of a chamber inlet; and, FIG. 2 is a top, right side perspective view of the chamber inlet of FIG. 1.

The broken lines shown in FIGS. 1 and 2 depict features of the chamber inlet that form no part of the claimed design.
